DENTAL HAND TOOL OR THE LIKE

Ralph G. Fontana, 7645 Giusti Road,
Forestville, Calif. 95436

Filed Mar. 15, 1967, Ser. No. 6,225

Term of patent 14 years

(Cl. D24—1)

FIG. 2

FIG. 1

FIG. 3

FIG. 4

FIG. 1 is a side elevational view of my ornamental design for a dental hand tool or the like.

FIG. 2 is a top plan view thereof;

FIG. 3 is a front elevational view thereof; and

FIG. 4 is a rear elevational view thereof.

In view of the prior art, it is understood that the characteristic features of my design reside in the overall shape of the dental hand tool or the like and particularly the asymmetry thereof, as best seen in FIG. 1.

I claim:

The ornamental design for a dental hand tool or the like, as shown.
